UNITED STATES PATENT OFFICE.

LOUIS J. BRUNE, OF ALGIERS, LOUISIANA.

RAILWAY-CAR-TOILET LOCK.

1,240,933.

Specification of Letters Patent. Patented Sept. 25, 1917.

Application filed May 15, 1917. Serial No. 168,817.

To all whom it may concern:

Be it known that I, LOUIS J. BRUNE, a citizen of the United States, residing at Algiers, in the parish of Orleans, State of Louisiana, have invented certain new and useful Improvements in Railway-Car-Toilet Locks; and I do hereby declare the following to be a full, clear, and exact description of the invention, such as will enable others skilled in the art to which it appertains to make and use the same.

This invention relates to improvements in toilets and particularly to toilets used on railway cars.

15 One object is to provide a novel and simple means for closing the receptacle or tank of the toilet bowl so as to prevent the matter from dropping on the tracks in depots or at way stations.

20 Another object is to provide means actuated by the application of the air brakes of the train which will close the receptacle, when the train stops, and which will open the receptacle when the train is again in motion and the brakes off.

Other objects and advantages will be apparent from the following description when taken in connection with the accompanying drawing.

25 The figure is an enlarged view of the invention, in section, shown in connection with the parts of the brake system of the car.

Referring particularly to the accompanying drawing 10 represents the floor of the railway car, 11 the bowl of the toilet, 12 the flush tank, and 13 the receptacle disposed below the car and connected to the bowl by the pipe 13'. The car is provided with the usual air reservoir 14 which supplies air to 30 the brake cylinders of the car, the brake cylinder 29, the triple valve 30, and the conductor's valve 31. At one end of the receptacle there is mounted a pivoted door 16 which is to be closed when the train is in a 35 depot or at a station so that the refuse from the toilet which enters the receptacle will not be discharged on the tracks. Mounted on the bottom of the car above the receptacle is a cylinder 17 in which is arranged a piston 18 carrying a piston rod 19 which extends through the rear of the cylinder and is pivotally connected to the upper end of an arm 20 carried by the upper portion of the said door 16. Surrounding the piston rod 50 and bearing with its ends against the piston

and the end of the cylinder is a strong coil spring 21, said spring normally pressing the piston toward the other end of the cylinder, so as to swing and hold the door 16 in open position.

6 Mounted on the floor of the car, adjacent the pipe 15, is a valve casing 22, and disposed in this casing is a sliding valve 23, said valve being formed with a vertical transverse passage 24 therethrough. Connected to the pipe 15 and to the upper side of the valve casing is a pipe 25, while a pipe 26 is connected to the lower side of the casing, directly opposite the pipe 25, and leads to the outer end of the cylinder 17. Between 7 one end of the valve and the end of the casing is a spring 27, said spring being equal to or slightly weaker in force than the normal air pressure in the pipe 15. Connected to the pipe 15, and entering the other end 75 of the valve casing is a pipe 28, this pipe permitting the full pressure of the air of the train pipe to enter the valve casing, at all times, to drive the valve to the other end of the casing, against the tension of the spring. 80 When the pressure in the train pipe is reduced, as when the brakes are applied to stop the train, the pressure of air through the pipe 28 from the train pipe 15, will be less than the force of the spring 27, which 85 results in the spring pushing the valve into position to register its passage 24 with the pipes 25 and 26 and thus permit air to flow directly through the pipes 25 and 26 from the train pipe 15 to the cylinder 17. This 90 results in driving the piston to the other end of the cylinder and the closing of the door 16. The door will remain in closed position as long as the brakes are set, but as soon as the brakes are released and the normal air pressure is restored in the pipe 15 by the pumps of the brake system, the spring 27 will be overcome and the valve driven thereagainst and held with its passage out of registry with the pipes 25 and 95 26. In the outer end of the cylinder 17 there is formed a small bleed opening 21' from which the air is exhausted into the atmosphere, and whereby the spring 21 is permitted to move the piston into normal position 100 to open the door 16.

Thus it will be seen that I have provided a novel and efficient device for preventing refuse from the car toilets from being dropped on the tracks in stations or depots, thus 110

obviating the necessity of the conductor or brakeman locking and unlocking the toilet doors when the car stops or starts.

What is claimed is:

- 5 The combination with an air-brake system and its train-pipe, of a toilet receptacle, a closure for the receptacle movable into and out of closing position, a cylinder having a piston connected with the closure
- 10 for actuating it, means for holding the piston normally and yieldably with the closure in inoperative position, said piston being

movable by air pressure in the cylinder to move the closure into operative position, and means operable by brake-applying 15 change of train-pipe pressure for communicating the cylinder with the train pipe.

In testimony whereof, I affix my signature in the presence of two witnesses.

LOUIS J. BRUNE.

Witnesses:
